Int. Cl. D3—01

U.S. Cl. D89—5 B

FIG. 1

FIG. 2

FIG. 3

FIG. 4

FIG. 5

FIG. 6

FIG. 1 is a front perspective view of an attache case showing my new design, the rear being substantially plain and unornamented except for the continuation of the strap element;

FIG. 2 is a top plan view;

FIG. 3 is a side elevational view thereof, the opposite side being a mirror image of the side shown;

FIG. 4 is a front perspective view showing a modified form of my new design, the rear being substantially plain and unornamented;

FIG. 5 is a top plan view; and

FIG. 6 is a side elevational view, the opposite side being a mirror image of the side shown.

The attache case is shown broken away in FIGS. 1, 2, 4 and 5 to indicate variable length.

I claim:

The ornamental design for an attache case, as shown and described.
